J. T. O'NEILL

RAILWAY BRIDGE PLATE

Filed March 7, 1925

Inventor

J. T. O'Neill.

Attorney

UNITED STATES PATENT OFFICE.

JOHN T. O'NEILL, OF JENKINTOWN, PENNSYLVANIA.

RAILWAY BRIDGE PLATE.

Application filed March 7, 1925. Serial No. 13,761.

To all whom it may concern:

Be it known that I, JOHN T. O'NEILL, a citizen of the United States, residing at Jenkintown, in the county of Montgomery and State of Pennsylvania, have invented 5 certain new and useful Improvements in Railway Bridge Plates; and I do hereby declare the following to be a full, clear, and exact description of the invention, such as 10 will enable others skilled in the art to which it appertains to make and use the same.

This invention relates to railway bridge plates, and has for one of its objects the provision of a novel, simple and inexpensive device of this character which shall be 15 adapted to reinforce a rail joint and prevent the rails from spreading or creeping and which shall be adapted to be readily secured in position for use.

With the above and other objects in view, the invention consists of the construction, combination and arrangement of parts hereinafter fully described and claimed, and 20 illustrated in the accompanying drawing,

25 wherein:

Figure 1 is a perspective view illustrating the application of a railway bridge plate constructed in accordance with my invention,

30 Figure 2 is a detail perspective view of the bridge plate,

Figure 3 is a longitudinal sectional view of the bridge plate, the plate being shown in position upon a pair of ties, and

35 Figure 4 is a view in end elevation of the bridge plate.

Corresponding and like parts are referred to in the following description, and designated in the several views of the accompanying drawing, by similar reference characters.

40 In the drawing 1 designates a pair of aligned railway rails and 2 a pair of the supporting ties therefor. The adjacent ends of the rails 1 are shown as meeting between the ties 2 and secured together by angle bars 3.

45 In order to support and thus strengthen the joint of the rails 1 and to prevent the rails from creeping or spreading, I provide an elongated flat plate 4 which rests upon the ties 2 and extends across the space between the ties beneath the rails. At its longitudinal or side edges, the plate 4 is

provided with upstanding flanges 5 which 55 contact with the lower outer edges of the angle bars 3. The plate 4 is provided with a plurality of openings 6 adapted to receive spikes 7 which contact with the angle bars 3 and enter the ties 2. At a point centrally 60 between its ends, the plate 4 is provided with an upwardly directed and transversely extending rib 8 which occupies a position between the adjacent ends of the rails 1 and the ends of which are spaced inwardly from 65 the flanges 5. A pair of angle bars 9 presenting horizontal members 10 and vertical members 11 are secured to the under side of the plate 4 with the vertical members in abutting relation. Rivets 12 which engage 70 the vertical members 11 and the plate 4 secure the angle bars 9 in place. The vertical members 11 of the angle bars 9 are located at the longitudinal center of the plate 4, and the angle bars are shorter than the plate. 75 The ends of the angle bars 9 are spaced for an equal distance from the ends of the plate 4.

The ends of the angle bars 9 contact with the opposing sides of the ties 2, and due 80 thereto the ties are held against casual movement in the direction of each other. As the plate 4 is spiked to the ties 2, and as the ends of the angle bars 9 contact with the opposing sides of the ties, the plate is 85 held against any casual movement with respect to the ties. The ribs 8 prevent the rails 1 from having any casual movement with respect to the plate 4 in an endwise direction, and the flanges 5 prevent the rails 90 1 from having any casual movement with respect to the plate 4 in a lateral direction. The angle bars 9 strengthen and reinforce that portion of the plate 4 located between the ties 2.

95 From the foregoing description, taken in connection with the accompanying drawing, it should be apparent that the bridge plate is strong, that it cannot have any casual movement with respect to the ties to which it is secured, that it will strengthen the joints of the rails, and that it will prevent the rails from creeping or spreading.

100 It should be understood that the drawing is merely illustrative and does not pretend to give exact proportions. Furthermore, the said drawing is illustrative of a preferred construction, it being my expectation that 105

various changes and modifications may be made without departing from the spirit and scope of the invention.

What is claimed is:—

5. 1. A bridge plate of elongated formation, said plate being provided at its side edges with upstanding flanges and at its center with an upstanding and transversely extending rib having its ends spaced from the flanges.
10. 2. A bridge plate provided with relatively spaced upstanding flanges and angle bars having vertical members depending from the under side of the plate.
15. 3. A bridge plate having upstanding flanges and an upstanding rib, the rib be-

ing arranged between the flanges and having its ends spaced from the flanges.

4. A bridge plate having upstanding flanges and a rib arranged between the flanges, angle bars located at the under side of the bridge plate and presenting horizontal members secured to the bridge plate and vertical members arranged in abutting relation.

In testimony whereof I affix my signature in presence of two witnesses.

JOHN T. O'NEILL.

Witnesses:

FRANCES O'NEILL,
FRANK P. O'DONNELL.
